UNITED STATES PATENT OFFICE.

LOUIS RAUHAUSER, OF BROOKLYN, NEW YORK.

STEAM-GENERATOR.

SPECIFICATION forming part of Letters Patent No. 739,445, dated September 22, 1903.

Application filed January 27, 1903. Serial No. 140,699. (No model.)

To all whom it may concern:

Be it known that I, LOUIS RAUHAUSER, a citizen of the United States, and a resident of Brooklyn, in the county of Kings and State 5 of New York, have invented certain new and useful Improvements in Steam-Generators, of which the following is a specification.

The invention relates to improvements in steam-generators; and it consists in the novel 10 features, arrangement, and combinations of parts hereinafter described, and particularly pointed out in the claims.

The object of the invention is to provide a steam-boiler in which the steam may be economically generated and which within a limited space will afford the maximum extent of 15 heating-surfaces for the water.

In accordance with my invention I provide a fire-box, a combustion-chamber containing 20 a set of tubes exposed to the action of the heat and through which the water passes, a boiler proper containing the body of water and the set of tubes through which the product of combustion from said chamber passes 25 on its way to the uptake, or stack, and suitable water-legs extending from one end of said boiler to one end of the tubes in the combustion-chamber and from the other end of said tubes in the combustion-chamber to said 30 boiler, whereby the water in the boiler surrounding the tubes therein is caused to circulate on a line downward through one water-leg, thence through the tubes in the combustion-chamber, and thence upward through the 35 other water-leg back to the boiler, the water being thus subjected to contact with the exterior surfaces of the boiler-tubes and the interior surfaces of the tubes in the combustion-chamber.

40 The invention will be fully understood from the detailed description hereinafter presented, reference being had to the accompanying drawings, in which—

Figure 1 is a vertical longitudinal section 45 through a steam-generator constructed in accordance with and embodying the invention, this section being on the dotted line 1 1 of Fig. 2. Fig. 2 is a front elevation of same, one of the doors leading to the hand-hole 50 plates for the combustion-chamber tubes being shown in an open position; and Fig. 3 is a rear end view, partly broken away, of same.

In the drawings, 10 designates the fire-box; 11, the general combustion-chamber; 12, the tubes disposed within the combustion-chamber; 13, the boiler; 14, the boiler-tubes; 15, the front water-leg extending from the boiler to the tubes 12; 16, the rear water-leg extending upwardly from the tubes 12 into the boiler 13 at a point above the set of tubes 14, and 17 the usual stack or uptake for the products of combustion.

The fire-box 10 will be provided with the usual grate-bars 18, a feed-door 19, and a usual pit-door 20, and at the rear end of said fire-box is 65 provided the vertical wall 21 which extends upwardly to a point about the middle of the bank of lower tubes 12, so that the products of combustion will be compelled thereby to ascend around and between the front portions of the tubes 12, and thence by a rear plate or wall 22 be compelled to descend around and between the middle portion of the tubes 12, and thence ascend around and between the rear portions of the tubes 12 to the upper portion 70 of the combustion-chamber 11, where said products of combustion will enter the boiler-tubes 14, and after traveling through said tubes 14 find an escape at the uptake 17. There are a large number of the tubes 12, as illustrated, and with the arrangement and construction shown this bank of tubes 12 is subjected throughout its extent to the action of the products of combustion, the latter being 75 compelled to take a serpentine course in repeated contact with said tubes, whereby said tubes, with the water flowing through the same, become properly heated without waste of fuel. The rear plate or wall 22 depends from about the rear end of the boiler 13 to a 80 point about the middle of the bank of lower tubes 12, as shown.

The boiler 13 is disposed over the fire-box 10 and extends rearwardly of the vertical plane of the wall 21, the lower walls of the 95 boiler being thus exposed to the action of the products of combustion, and said boiler at the lower side of its front portion is provided with the opening 23, leading to the front water-leg 15, which is formed between the plates 24 and 25, as shown in Fig. 1, and communicates with all of the tubes 12, the latter at their front ends being secured within apertures in the plate 25, while the plate 24, in line with

the front ends of said tubes 12, is apertured and provided with hand-hole plates, there being one hand-hole plate for the front end of each tube 12, and these hand-hole plates 5 being normally concealed behind the front doors 26. Upon the opening of the doors 26 the hand-hole plates will be exposed, as represented in Fig. 2.

The lower ends of the plates 24 25 are bent 10 inwardly toward each other to form the lower end of the front water-leg, and, as shown in Fig. 1, the said inwardly-bent portions overlap each other and are riveted together. The upper end of the plates 24 25 are formed with 15 flanges extending outwardly from each other and conforming to the adjacent surfaces of the boiler, to which they are riveted. The upper ends of the plates 24 25 constitute a cradle receiving and supporting the front end 20 of the boiler, and the lower ends of these plates are supported by the masonry over the feed-door 19.

The rear water-leg 16 is formed between the broad plates 27 28 and is in communication 25 with the rear ends of all of the tubes 12, the rear ends of said tubes 12 being secured within apertures in the plate 27, while in the plate 28 hand-hole plates are provided in line with each of the tubes 12. The plates 27 28 are 30 properly braced and secured by suitable stay-bolts 29, and the upper ends of these plates are curved frontwardly to engage and be secured to the rear end of the boiler 13, an opening 30 being provided in the rear end of the 35 boiler for the passage of the water from the rear leg 16 into said boiler. The lower end of the water-leg 16 is securely riveted to a mud-drum 31, which is mounted in saddles 32, resting upon ball-bearings 33, supported 40 upon masonry 34. The mud-drum 31 is in communication with the lower end of the water-leg 16 and provided with hand-hole plates at its ends for enabling at the proper time the convenient cleaning out of the drum.

45 The tubes 14 are secured at their rear ends in holes formed in the rear end of the boiler 13 and at their front ends in holes formed in the front plate 35 of the boiler in a usual manner, and the rear ends of the tubes 14 are 50 in free communication with the upper rear portion of the combustion-chamber 11, while the front ends of said tubes 14 open into the chamber 36, from which the stack or uptake 55 17 leads. The rear water-leg 16 forms the rear wall of the combustion-chamber 11, and the upper forwardly-curved portion of said leg closes the top of the upper rear portion of said chamber and compels the products of combustion to enter the tubes 14, the upper 60 end of said leg being above said tubes.

The chamber 36 is cylindrical in outline, and its horizontal walls are about in line with the cylindrical walls of the boiler, and the front end of this chamber is provided with a 65 door, as shown, in line with the bank of boiler-tubes 14. The chamber 36 projects forwardly of the boiler, and its cylindrical shell is at

its inner end riveted to the shell of the boiler, as shown in Fig. 1. The uptake or stack 17 is secured to the top of the shell forming the 70 chamber 36.

The tubes 14 are secured to the front and rear plates or heads of the boiler and extend at right angles thereto, and the tubes 12 are secured at their ends in apertures formed in 75 the inner plates of the front and rear water-legs and extend at right angles to said plates, this arrangement of the tubes 12 being deemed very important in the successful construction and operation of the generator.

80 The operation of the generator will probably be fully understood from the description hereinbefore presented. The fire will be started upon the grate-bars 18, and the products of combustion will ascend around and about the 85 front portions of the tubes 12 and under the boiler 13, and thence along the lower sides of the boiler and down around and between the middle portions of the tubes 12, and thence 90 up, around, and between the rear portions 95 of the tubes 12 to the rear end of the boiler, where the hot products will pass through the boiler-tubes 14 and enter the chamber 36, whence they will escape through the stack or uptake 17. The upper end of the rear water-leg 16 is on a gradual curve above the lower tubes 14 and compels the hot products to as evenly as possible pass through all the tubes 14, the space between the rear end of the boiler and the upper part of the water-leg 16 gradually lessening as the upper end of said leg approaches the end of the boiler. The gradual inward curvature of the upper portion of the rear water-leg 16 also facilitates the circulation of the water, which in the construction 100 described moves upwardly through the said leg 16. The water will be supplied to the boiler in the usual manner and will pass around and between the tubes 14 therein, and thence circulate downward into the front water-leg 15 and into and through the tubes 12 to the rear water-leg 16, up through which the water will pass to the boiler 13, there thus 105 being a circulation of the water and an exposure of the water to the heating action of 110 the tubes 12 and 14. With the construction 115 presented maximum heating-surfaces for the water are provided, and the latter is enabled to absorb the maximum amount of heat produced at the fire-box 10. My invention, 120 therefore, produces means for generating steam in an economical manner and with the maximum efficiency and within a limited amount of space, one purpose of the invention being to secure the increased heating-surfaces 125 without the employment of an undue amount of space.

What I claim as my invention, and desire to secure by Letters Patent, is—

130 1. The steam-generator comprising the fire-box and combustion-chamber, combined with the boiler 13 disposed over said combustion-chamber and containing the series of longitudinal tubes 14 at one end communicating

with said combustion-chamber and at the other end with the uptake, the front water-leg 15 comprising the parallel plates and communicating with and extending downwardly 5 below one end of said boiler, the rear water-leg 16 formed of the plates 27, 28, constituting the rear wall of the combustion-chamber and at their upper portions turning forwardly to engage and communicate with said boiler 10 above the tubes 14 therein, and the bank of tubes 12 extending lengthwise of said combustion-chamber and at their front ends communicating with the water-leg 15 and at their rear ends with the rear water-leg 16, said 15 tubes 12 being arranged at right angles to the facing-plates of said water-legs, and said rear water-leg being closed except where it communicates with said tubes 12 and with said boiler above the tubes 14 therein, substantially as set forth.

2. The steam-generator comprising the fire-box and combustion-chamber, combined with the boiler 13 disposed over said combustion-chamber and containing the series of longitudinal tubes 14 at one end communicating with said combustion-chamber and at the other end with the uptake, the front water-leg 15 comprising the parallel plates and com-

municating with and extending downwardly below one end of said boiler, the rear water-leg 16 formed of the plates 27, 28, constituting the rear wall of the combustion-chamber and at their upper portions turning forwardly to engage and communicate with said boiler above the tubes 14 therein, the bank of tubes 35 12 extending lengthwise of said combustion-chamber and at their front ends communicating with the water-leg 15 and at their rear ends with the rear water-leg 16, the rear wall 21 of the fire-box extended upwardly to a 40 point about the middle of said bank of tubes 12, and the depending rear wall 22 extending downwardly to about the middle of said bank of tubes 12, said tubes 12 being arranged at right angles to the facing-plates of said water-legs, and said rear water-leg being closed except where it communicates with said tubes 12 and with said boiler above the tubes 14 45 therein, substantially as set forth.

Signed at New York, in the county of New 50 York and State of New York, this 26th day of January, A. D. 1903.

LOUIS RAUHAUSER.
